UNITED STATES PATENT OFFICE.

WILLIAM G. KENDALL, OF NEWARK, NEW JERSEY.

ROUGE-PAD HOLDER.

1,236,844.

Specification of Letters Patent. Patented Aug. 14, 1917.

Original application filed July 31, 1916, Serial No. 112,348. Divided and this application filed November 2, 1916. Serial No. 129,162.

To all whom it may concern:

Be it known that I, WILLIAM G. KENDALL, a citizen of the United States, residing at Newark, in the county of Essex and State 5 of New Jersey, have invented certain new and useful Improvements in Rouge-Pad Holders, of which the following is a specification.

My invention is a division of a copending application filed by me July 31, 1916 and bearing the Serial No. 112,348 and relates to new and useful improvements in compressed powder holders, the primary object of my invention being the provision of 15 a simple and improved method of packaging toilet powder, rouge and similar articles in compressed form.

More specifically, my invention includes an ornamental box or container, preferably 20 formed of sheet metal and means lockingly held in the box for detachably securing a pad holding a cake of powder so that after the powder has been used from the pad, the pad may be withdrawn and replaced by a 25 fresh one.

In this connection, a still further object of my invention consists in providing a device which is detachably applied within the box and which will detachably and lockingly 30 receive a powder holding pad.

Another object of my invention is to provide an anchoring device of the above described character of such construction that it may be stamped or otherwise formed in a 35 single piece from sheet metal or other suitable material.

With these and other objects in view my invention will be more fully described, illustrated in the accompanying drawings, and 40 then specifically pointed out in the claims which are attached to and form a part of this application.

In the drawings:

Figure 1 is a central vertical sectional 45 view taken through a container equipped with my compressed powder holding device:

Fig. 2 is a perspective view of the anchoring device proper.

Corresponding and like parts are referred 50 to in the following description and indicated in all the views of the drawings by the same reference characters.

Referring more specifically to Fig. 1, 10 indicates a container or box which is preferably formed of cardboard and which has a

circular bottom 11, an inner peripheral wall 12 and an outer peripheral wall 13, of less height than the inner wall whereby an exterior stop shoulder 14 is provided to receive the annular flange 15 of the cover 16. This 60 cover may be either hinged to the box or not, as preferred, and a clamping ring 17, also preferably of cardboard, engages within the flange 15 and secures a mirror 18 in place within the cover. The engagement 65 of the flange 15 with the shoulder 14 prevents the ring 17 being forced into undue engagement with the mirror 18 and so avoids any likelihood of injury to the mirror through too close shutting of the cover. 70

My present invention consists primarily in providing means for securing a powder or rouge holding pad 19 within the above box. This pad, which may be formed of cardboard or other suitable material, is circular 75 in shape and provided with an outwardly extending peripheral flange 20 which lockingly receives powder or rouge pressed against the upper face of the pad. The anchoring member employed includes the disk-shaped body 21, preferably formed of sheet metal and provided at peripherally spaced intervals with radially extending tongues 22 which, in spaced relation to the edge of the body, are bent upwardly, as shown at 80 23. The pad is inserted between the upwardly directed arms of the holder 21 and the terminals of the arms are then bent inwardly, as shown at 24 in Fig. 1, to lock the pad to the holder. If desired, the pad may 85 be additionally anchored to the holder by providing the holder with diametrically opposed V-shaped clefts 25 defining triangular shaped prongs 26 which are bent upwardly, passed through the bottom of the pad and then rebent, as clearly shown in Fig. 1. The body of the holder is also provided with a second pair of diametrically disposed V-shaped clefts 27 defining triangular tongues or prongs 28 which are bent downwardly, 90 passed through the bottom of the box and rebent to anchor the holder to the box. 95

From the foregoing description, taken in connection with the drawings, the construction and method of employing the powder holder will be readily understood. Although I have illustrated and described it in all its details, it will of course be understood that I reserve the right to make any changes, within the scope of the appended claims. 105 110

Having thus described the invention, what is claimed as new is:

1. The combination with a box and a compressed powder holder having a marginal flange, of an anchoring device including a body having downstruck prongs passed through the bottom of the box and bent against the lower face thereof and upstruck prongs passed upwardly through the bottom of the holder and bent against the upper face thereof.
2. The combination with a box and a compressed powder holder having a marginal flange, of an anchoring device including a body having downstruck prongs passed through the bottom of the box and bent against the lower face thereof and upstruck prongs passed upwardly through the bottom of the holder and bent against the upper face thereof, and arms formed at intervals about the edge of the body and bent up-

wardly and inwardly to engage over the edge of the holder.

3. The combination with a box and a compressed powder holder having a marginal flange, of an anchoring device including a body adapted to seat in the bottom of the box and having arms adapted to be bent upwardly and inwardly about the marginal flange of the holder, and means for anchoring the body within the box.

4. The combination with a box and a compressed powder holder having a marginal flange, of an anchoring device including a body having upstruck prongs adapted to be passed inwardly through the bottom of the holder and bent against the upper face thereof, and means carried by the body for locking it in the box.

In testimony whereof I affix my signature.

WILLIAM G. KENDALL, [L.S.]
